INVENTOR.

BY

O. V. Thorne

ATTORNEY.

UNITED STATES PATENT OFFICE

EMANUEL BLAUHORN, OF VIENNA, AUSTRIA

EXHAUST-STEAM INJECTOR

Application filed September 22, 1927, Serial No. 221,381, and in Austria February 5, 1927.

The subject of this invention is a modification of the exhaust steam injector described in the application for United States patent, filed by Hans Deutsch, September 15, 1927, 5 under Serial Number 219,739, having an annular nozzle fed with live steam and enclosing the exhaust steam nozzle.

The arrangement there disclosed has the disadvantage, particularly with smaller sizes, that the annular space between the exhaust steam nozzle and the annular nozzle is rapidly worn out by the action of the steam flowing through this narrow section, the function of the apparatus being thereby injured as the exact cross-sectional area is important. The present invention therefore has the object of providing a form of the apparatus in which this difficulty is removed. The underlying thought is to permit the annular nozzle to function only at those periods at which it performs its principal purpose, which is to ensure starting of the injector even after air or certain amounts of steam have entered through the exhaust steam connections; while at all other periods while the injector is in operation the entrance of steam to the nozzle is prevented, so that even when no exhaust steam is present the live steam replacing it reaches the injector only through the ordinary path but not through the lifting nozzle.

As the periods of time in which the lifting nozzle is in action will thus be only very brief, the wear on the cross-sectional area will be so small even without taking any particular precautions that it may be disregarded.

This inventive idea is most advantageously carried out by giving a suitable form to the arrangement which regulates the admission of the auxiliary live steam to the injector. The form given to this arrangement is such that the admission of the auxiliary live steam to the lifting nozzle and to the exhaust steam space can occur only alternately in such a way that each time the valve is manipulated the live steam path to the lifting nozzle is first opened and then this path is simultaneously closed off while the path for the live steam into the exhaust

steam space is opened so that the lifting of the feed water is always first assured in the manner described below when the injector is changed over from exhaust steam operation to operation with expanded live steam.

The drawings illustrate the subject-matter of the invention applied to an injector of the general type disclosed in United States Patents Nos. 944,455 and 1,342,128 granted December 28, 1909 and June 1, 1920 respectively, to J. C. Metcalfe, et al., modified to include the lifting feature disclosed in the Deutsch application referred to. It is to be understood, however, that the present invention may also be applied to exhaust steam injectors, the specific details of which differ from those disclosed in the Metcalfe patents. Fig. 1 is a diagrammatic view of an injector and control valve assembly in which the present invention is incorporated, while Figs. 2 and 3 are enlarged details of an illustrative form of the control valve embodying the invention in its two main positions.

In the injector shown in Fig. 1 the nozzle 8, fed from the steam space 3 to which exhaust steam is admitted through valve 3^a, is surrounded by the annular nozzle 9 which acts on the water space 4 the latter being supplied from the water pipe 19. This nozzle is supplied with live steam by its own supply pipe 20 while the auxiliary live steam is carried to the exhaust steam space 3 through the passage 18.

The valve, however, which controls the steam path to the passages 18 and 20, is provided with an extension in the form of a hollow piston *a* whose wall is provided with openings *b*, *b*₁ and *c*, *c*₁, of which the openings *c*, *c*₁, communicate with the path 20 when the valve 16 is in its lowest position, while the openings *b*, *b*₁ communicate with the path 18 when the valve is opened. In the latter position the openings *c*, *c*₁ are closed.

Fig. 2 shows the position of this controlling valve when the valve 16 is just beginning to open. Steam flows through the passage 2, under the seat of the valve into the hollow piston to the openings *c*, *c*₁ and through these into the steam path 20 whence it reaches the

lifting nozzle 9. This current of steam then lifts the water which reaches the water space 4 of the injector through the water pipe 19. With a further opening of the valve 16 the 5 piston assumes the position of Fig. 3 in which the flow of steam to the lifting nozzle ceases and the way is opened through pipe 18 to the exhaust steam space 3 of the injector, where this 10 expanded auxiliary live steam, replacing the exhaust steam, assures the action of the injector in the ordinary way in connection with the live steam flowing through the nozzle 7.

The form of the controlling valve herein 15 illustrated has the advantage that it controls with a single apparatus not only the opening of the live steam path itself, but also several other paths in the proper order and in addition makes it possible by the proper dimensioning of the openings in the wall of the 20 valve to secure the required throttling down of the steam for each of the passages. Through this co-action of the solid valve and its sleeve portion, it now becomes unnecessary to pack the latter so that the construction is 25 very simple.

I claim:

1. In an injector of the class described, the combination of a main low pressure steam nozzle, a steam space communicating there- 30 with, a high pressure lifting nozzle surround- ing said main nozzle, conduits to supply said steam space and said lifting nozzle with live steam, and valve means for admitting live steam to said conduits in alternation only.
- 35 2. A combination according to claim 1, the valve means being so arranged that the flow through the conduit to the high pressure lifting nozzle is always opened first on admitting live steam.
- 40 3. A combination according to claim 1, the valve means comprising a disc to close the entrance to both conduits, and a hollow piston with openings to admit steam to its interior and to permit flow from its interior to the 45 two conduits.
- 45 4. A combination according to claim 1, the valve means comprising a hollow piston with an opening to admit steam to its interior and openings to permit flow from its interior to 50 the two conduits, the latter openings being of such dimensions as to throttle the live steam down by the required amount.

EMANUEL BLAUFORN.
